DESIGN FOR A VALVE FOR FLUSH TANKS

Herman Rosenthal, Ansonia, Conn.

Application July 31, 1937, Serial No. 70,764

Term of patent 14 years

To all whom it may concern:

Be it known that I, Herman Rosenthal, a citizen of the United States and residing at Ansonia, in the county of New Haven and State of Connecticut, have invented a new, original, and ornamental Design for a Valve for Flush Tanks, of which the following is a specification, reference being had to the accompanying drawing, forming part hereof, and in which

Fig. 1 is a top plan view of the valve for flush tanks, showing my new design,

Fig. 2 is a side elevational view of the valve for flush tanks,

Fig. 3 is a bottom view of the valve for flush tanks.

The dominant feature of my design resides in the stepped top portion of the valve for flush tanks merging with the conical bottom as shown.

I claim:

The ornamental design for a valve for flush tanks, substantially as shown and described.

HERMAN ROSENTHAL.
